UNITED STATES PATENT OFFICE.

ARTHUR H. ADAMS, OF SPARKILL, NEW YORK, ASSIGNOR TO WESTERN ELECTRIC COMPANY, OF NEW YORK, N. Y., A CORPORATION OF ILLINOIS.

IMPULSE-SENDING MECHANISM.

1,164,625.

Specification of Letters Patent. Patented Dec. 21, 1915.

Application filed November 30, 1914. Serial No. 374,682.

To all whom it may concern:

Be it known that I, ARTHUR H. ADAMS, a citizen of the United States, residing at Sparkill, in the county of Rockland and State of New York, have invented certain new and useful Improvements in Impulse-Sending Mechanisms, of which the following is a full, clear, concise, and exact description.

10 This invention relates to impulse-sending mechanism, and more particularly to what is known as an overlapping cycle impulse-sending mechanism, that is, one in which the dial or actuating means may be set for a 15 subsequent series of impulses, while the impulse mechanism is operating to send out a previous set of impulses.

The object of this invention is in general to provide a device of this class which will 20 be simple, compact and efficient.

In accordance with the general features of this invention, there is provided a dial or actuating member, and impulse-transmitting mechanism, and a driving means interposed 25 between the actuating member and the impulse-transmitting means. The operation of the actuating mechanism serves to store power in the driving mechanism for operating the impulse mechanism after the actuating 30 mechanism has returned to normal position.

Means are provided for preventing effective operation of the actuating means during the operation of the impulse-sending mechanism to send out impulses. This feature consists of mechanism which is automatically brought into position before the beginning of the rotation of the impulse-sending means to prevent the engagement of the actuating 40 means with the driving means. Means are also provided for locking the actuating means in a subsequently operated position during the operation of the impulse-sending mechanism in response to a previous operation of said actuating device, said locking means being released as soon as said impulse-sending mechanism reaches normal position. Governing means are also provided for controlling the speed of the mechanism when it 50 is being set, and when it is operating to send out impulses. This means preferably comprises a governor which is adapted to permit the device to rotate at a relatively high speed during the preliminary or set-

ting movement, and at a slower speed when sending out impulses.

Other features of the invention are the details of construction and combination of parts of the motor mechanism for driving the parts, and the interconnection of these parts.

In the drawings—Figure 1 is a perspective view with parts broken away of a transmitter embodying the features of this invention: Fig. 2 is a sectional view of the device 65 taken upon line 2—2 of Fig. 3; Fig. 3 is a view in side elevation of the device with parts in section; Figs. 4, 5, 6 and 7 are detail views of the connecting and actuating means of the device; Fig. 8 is a sectional view 70 taken upon line 8—8 of Fig. 5; Fig. 9 is a detail view of the governing apparatus; Fig. 10 is a fragmentary detail view of parts of the actuating and connecting devices; and Fig. 11 is a longitudinal cross-sectional view 75 of the device.

In the drawings, 5 designates a cylindrical casing member to which are attached front and back plates 6 and 7. Attached centrally of the back plate 7 and extending through the casing is a stud 8 for rotatably supporting the various elements of the device, as will be hereinafter pointed out.

Secured to the outer end of a thimble 10, which extends over the forward end of the stud 8 and is rotatable thereon, is a finger wheel or dial 11 having a plurality of openings 12, 12 which, when the dial is in normal position, are opposite numerals 1 to 0 inclusive upon the front face of the frame 90 plate 6. Upon the inner end of the thimble 10 is secured a disk 13 having a plurality of teeth 14, 14 in its periphery. Secured to the disk 13 is an arm 15 carrying at its outer end a pivotal pawl 16 which, when the disk 95 13 is in normal position, is pressed outwardly by a stop member 17, but is adapted to be moved inwardly when away from the stop by means of a spring 18.

Located adjacent the inner end of the thimble 10 (see Fig. 11) is a rotatable sleeve 20 carrying a disk 21 having teeth 22, 22 in its periphery adapted to be engaged by the pawl 16 when the disk 13 is moved away from normal position. A second disk 25, 105 having notches 26, 26 in its periphery, is mounted adjacent the disk 21 upon a sleeve 27, which is rotatable upon the stud 8. The

sleeve 27 is connected with a second sleeve 29 also rotatably mounted upon the stud 8. Carried by this sleeve 29 is a gear wheel 30 and an interrupter wheel 31. The gear 5 wheel 30 meshes with a pinion 32 upon a stud 33 carried by a bracket 34. Mounted upon the stud 33 is a gear 35 meshing with a worm 36 upon the shaft 37 of a centrifugal governing device 38. The interrupter wheel 10 31 is adapted to engage a contact-controlling device 40 in one direction of its movement to operate contact springs 41 and 42.

In the operation of the device the finger wheel 11 is rotated in a forward or clockwise direction in the usual manner until the finger of the operator reaches a stop 50. The rotation of the finger-wheel rotates the disk 13 and winds a spring 51 which, when the disk 50 is released, rotates the dial 11 15 and disk 13 to normal position. The disk 13 in its forward movement carries with it the pawl 16 which, when it moves away from the stop 17, is moved inwardly in position to engage the notches 22, 22 and 26, 26 in 20 the periphery of the disks 21 and 25. Upon the release of the dial by the operator, the pawl 16 falls into notches in the disks 21 and 25, and these disks are rotated in a counter-clockwise direction under the power 25 stored in the spring 51. This rotation of the disks 21 and 25 causes the winding up of a second spring 54, which stores the power necessary to return the disks 21 and 25 to 30 normal position when the finger-wheel and disk 11 are released therefrom, due to the engagement by the pawl 16 with the stop 17.

As hereinbefore stated, the disks 21 and 25 are capable of being angularly displaced with respect to each other, but they are normally held with the notches 22, 22 and 26, 26 in coincidence in the following manner: When the disks 21 and 25 are in normal position, a stop arm 53 on the disk 25 engages the stop 17 to hold the said disk in normal 40 position, while a stop pin 56, carried by the disk 21, extends through a notch 57 in the disk 25 and is held against one side thereof by a tensioned spring 58 attached at one end to the disk 21, and at its other end to the 45 disk 25. A second spring 59, connected at one end with the disk 13 and at its other end with the disk 21, tends normally to hold the disk 21 with the pin 56 in engagement with the lower side of the slot 57 while the engagement of the pawl 16 with coinciding notches 22 and 26 of the disks 21 and 25, 50 prevents relative movement of these disks while they are being moved by said pawl 16. As soon, however, as the pawl is released from said disks 21 and 25 and they start backward under the power of the spring 51, the spring 58 will exert sufficient force to move the disk 21 relative to the disk 25 so that pin 56 comes in engagement with 55 the upper side of the slot 57, thereby separating

the notches of the two disks to prevent the reengagement therewith of the pawl 16 until said disks have reached normal position with the disk 25 against the stop 17. When this occurs the spring 59 will draw the disk 21 a sufficient distance forward to bring the stop pin 56 back against the lower side of the notch 57 and thus again bring the notches of the two disks in alignment.

As the disks 21 and 25 move forward in 75 response to the action of the spring 51, the gear wheel 30 and the interrupter wheel 31 are rotated in a counter-clockwise direction. The rotation of the interrupter wheel 31 in this direction has no effect upon the contact 80 springs 41 and 42, since it is in a direction to push the contact-controlling device 40 away from instead of toward the contact springs. The rotation of the gear wheel 30, however, drives the gear wheel 35, which, 85 through the worm 36, drives the centrifugal governing means 38. As will be noted particularly by reference to Fig. 9, the shaft 37 of the governing device 38 is longitudinally movable in its bearings 60 and 61, and will 90 be moved in the direction of rotation of the gear wheel 35. Coöperating with the centrifugal device are two cylindrical bearing surfaces 62 and 63 of different diameters, the engagement of the centrifugal device 38 95 with the larger of the chambers 62 permitting a high speed, while its engagement with the chamber 63 limits its rotation to a much lower speed. When the various rotatable members are rotating in a counter-clockwise 100 direction, which is the direction of the return movement of the setting dial, the centrifugal device is moved into position to engage the chamber 62, whereby the parts may be rotated at a high speed.

When the pawl 16 is disengaged from the disks 21 and 25, and they start on their return movement in a clockwise direction, the interrupter wheel is moved in a direction to cause the opening and closing of the contact 110 springs 41 and 42 to send out current impulses in accordance with the setting of the dial 11. This movement also moves the governor shaft 37 longitudinally in its bearings 60 and 61 to bring the centrifugal governor 115 member into engagement with the smaller diameter cylindrical surface 63, whereby the speed of the parts, when sending out impulses, is greatly reduced.

After the dial 11 has been returned to 120 normal position and the pawl 16 is released from engagement with the disks 21 and 25, said dial 11 is free to be rotated for the purpose of setting the mechanism from another series of impulses. The pawl 16, however, 125 being prevented from reengaging the disks 21 and 25 while they are being returned to normal position in response to a previous operation of the finger dial 11, means are provided for locking said finger dial in a 130

subsequently actuated position until said disks 21 and 25 have returned to normal position as clearly shown in Figs. 4, 5, 6 and 7. The locking of the dial 11 in its advanced 5 position is accomplished by means of a pawl 70 pivotally supported in a stationary frame member 71. This pawl is adapted to be swung in one direction by means of projection 72 carried by the disk 13, which engages 10 a pin 73 projecting from said pawl 70 while an arm 74, carried by the disk 21, is adapted to engage the end of said pawl 70 to swing it in the opposite direction. A spring 75 is adapted to retain said pawl in 15 whichever position it assumes when the projection 72 and arm 74 are disengaged therefrom. Assuming now that the disk 13 is in its normal position with the projection 72 engaging the pin 73 of the pawl 70, and the 20 disks 21 and 25 are in an advanced position. The arm 74 being out of engagement with the tail of the pawl 70, said pawl will be swung forwardly with the spring 75 inside of the pivotal point of said pawl 70. If 25 now the dial 11 is moved it will move the disk 13 and with it the arm 72, so that the pawl 70 will be in a position to engage the notches or teeth 14, 14. The disks 21 and 25 being off normal position and moving in a 30 return direction, the notches 22 and 26 will be separated so that the pawl 16 will ride over the peripheral surfaces of these disks. The dial 11 being moved to the position desired before the said disks 21 and 25 have 35 reached normal position, the pawl 70 will engage one of the notches 14 of the disk 13 and retain said dial in such advanced position. As soon, however, as the disks 21 and 25 return to normal position the arm 74 en- 40 gaging the tail of the pawl 70 will disengage said pawl from the disk 13, and since the disks 21 and 25 undergo a relative movement upon reaching normal position, which brings the notches 22 and 26 into coincidence, the pawl 16 may engage these disks 45 21 and 25 to send out the impulses corresponding to the last setting of the device.

What is claimed is:

1. In an impulse transmitter, an interrupter movable in forward and backward directions, contact springs operated by said interrupter in one direction of movement to send out current impulses, setting means for moving said interrupter in one direction to set the transmitter, means operating independently of said setting means to move said interrupter in the opposite direction to send out current impulses, means permitting the movement of said setting means during the movement of said interrupter to send out impulses, and means for preventing the engagement of said setting mechanism with said interrupter during the sending out of impulses, whereby said setting mechanism 55 may be moved to any predetermined posi-

tion during the sending out of impulses in response to a previous setting.

2. In an impulse transmitter, an interrupter mechanism, setting means for said interrupter movable in forward and backward 70 directions, connecting means interposed between said setting means and said interrupter for causing the setting of said interrupter during backward movement of said setting means, means for disengaging said 75 setting means from said connecting means when said setting means returns to normal position, means for driving said connecting means and said interrupter in a reverse direction to send out impulses, means permitting 80 a second movement of said setting means during the reverse movement of said connecting means and said interrupter, and means for preventing the engagement of said setting means with said connecting 85 means during the reverse movement of said connecting means and said interrupter but permitting such engagement at the end of each reverse movement.

3. In an impulse transmitter, an interrupter, driving means therefor, an actuating means operable independently of said impulse sending member to cause the operation of said driving means, means for preventing the engagement of said actuating means 95 with said driving means during the movement of said interrupter, and means for holding said actuating means in an advanced position to which it may be moved during the impulse-transmitting movement 100 of said transmitting member, whereby the transmitter may be set for a succeeding operation before the completion of a previous one.

4. In an impulse transmitter, an interrupter, driving means therefor operable in forward and backward directions, actuating means operable independently of said driving means for moving said driving means in a forward direction, means for preventing 105 the engagement of said actuating means with said driving means during the backward movement of said driving means, and locking means effective during the backward movement of said driving means to maintain said actuating means in a position to which it may be moved during the movement of said interrupter, whereby the transmitter may be set for a succeeding operation 110 before the completion of a previous one.

5. In an impulse-transmitting mechanism, an impulse-transmitting member, a driving means operable in forward and backward directions, an actuating means movable in forward and backward directions, means operated by said actuating means in its backward movement to cause the forward movement of said driving means, means for disengaging said actuating means from said 125 driving means at the end of the backward 130

movement of said actuating means to permit the backward movement of said driving means, an interrupter operated by said driving means in its backward movement to send out current impulses, means operating automatically upon the backward movement of said driving means to prevent the reengagement therewith of the actuating means until said driving means has reached normal position, locking means for maintaining said actuating means in a forward position to which it may be moved during the backward movement of said driving means, and means operated automatically upon the return of said driving means to normal position to release said locking means and permit said actuating means to engage said driving means to actuate said interrupter and send out a series of impulses for which the device 20 was prepared during the sending out of previous impulses.

6. In an impulse transmitter, an interrupter movable in forward and backward directions, contact springs operated by said interrupter in its backward movement to send out current impulses, a setting mechanism movable in forward and backward directions, a clutch mechanism connected with said interrupter and adapted to be driven by said setting mechanism in its forward movement to move said interrupter in a forward direction, means for releasing said clutch mechanism from said setting mechanism, means for driving said clutch and interrupter mechanisms in a backward direction to send out impulses, and means for rendering such clutch mechanism ineffective with respect to said setting mechanism during the sending out of impulses, whereby the setting 40 mechanism may be moved to any predetermined position during the effective operation of the interrupter.

7. In an impulse transmitter, an interrupter rotatable in forward and backward directions, contact springs operated by said interrupter in its backward movement to send out current impulses, a rotatable member carrying said interrupter, a second rotatable member operable independently of said first-mentioned rotatable member, a setting mechanism carried by said second rotatable member, a pair of clutch members on said first mentioned rotatable member, a clutch member on the second-mentioned rotatable member adapted to engage the clutch members of the first-mentioned rotatable

member to rotate said interrupter in one direction, means operating automatically to disengage the several clutch members, means for rotating said interrupter in the opposite direction from its first movement, means for moving the clutch members of the first-mentioned rotating member relative to each other to prevent the engagement therewith of the clutch member of the second-mentioned rotatable member, and locking means controlled by the relative movement of the several clutch members to hold the clutch member of the second-mentioned rotatable member in any position to which it may be advanced during the rotation of the interrupter to send out impulses.

8. In an impulse transmitter, an interrupter movable in forward and backward directions, contact springs operated by said interrupter in one direction of movement only, and a governing means for limiting the movement of said interrupter to a determined high-speed when moving in one direction and to a limited low speed when moving in the opposite direction, said means comprising a centrifugal element, a plurality of cylindrical walls of different diameters for engaging said centrifugal element, and means operated by said interrupter for moving said centrifugal member into engagement with the separate walls, whereby said high and low speeds are obtained.

9. In an impulse transmitter, an interrupter movable in forward and backward directions, contact springs operated by said interrupter in one direction of movement only, and a governing means for limiting the movement of said interrupter to a determined high-speed when moving in one direction and to a limited low speed when moving in the opposite direction, said means comprising a centrifugal element, a pair of cylindrical walls of different diameters for engaging said centrifugal element, and means operated by said interrupter for moving said centrifugal member into engagement with the smaller of said walls to produce said low speed and into the larger of said walls to produce said high speed.

In witness whereof, I hereunto subscribe my name this 28th day of November, A. D. 1914.

ARTHUR H. ADAMS.
